TRIMMER MECHANISMS FOR SEWING MACHINES

Richard P. Graham, Stratford, Conn., assignor to The Singer Manufacturing Company, Elizabeth, N. J., a corporation of New Jersey

Application February 27, 1952, Serial No. 273,603

10 Claims. (Cl. 112—123)

The present invention relates to sewing machines and has for a primary object to provide an improved trimmer actuating mechanism for sewing machines.

More specifically, the present invention has for an object to provide a trimmer actuating mechanism in which the stroke of the trimmer blade can be readily adjusted to correspond to any changes in the stitch length as determined by the setting of the feed-advance mechanism. This has been accomplished by providing a common actuating means for both the trimmer and feed-advance mechanism. Thus, any variations in the stitch length automatically results in a corresponding variation in the stroke of the trimmer. This results in a tendency to prolong the useful life of the trimming blade by varying the cutting-edge travel of the movable blade relative to the ledger blade.

It is a further object of the present invention to provide a combined trimmer actuating and feed-advance mechanism composed of relatively simple mechanical expedients that are practical and economically feasible.

Having in mind these and other objects that will be evident from an understanding of this disclosure, a presently preferred embodiment of the invention is hereinafter set forth in such detail as to enable those skilled in the art to readily understand the function, operation, construction and advantages of it when read in conjunction with the accompanying drawings in which:

Fig. 1 is a vertical sectional view longitudinally of a sewing machine that embodies the present invention, with the certain parts of the machine broken away to illustrate the invention more clearly.

Fig. 2 is a sectional view taken substantially on the line 2—2 of Fig. 1, with the take-up guard of the machine removed.

Fig. 3 is a sectional view taken substantially on the line 3—3 of Fig. 1 with parts broken away.

Fig. 4 is a sectional view taken substantially on the line 4—4 of Fig. 1.

Fig. 5 is a sectional view taken substantially on the line 5—5 of Fig. 3 that illustrates a detail of the machine.

Fig. 6 is a sectional view taken substantially on the line 6—6 of Fig. 3.

Fig. 7 is a diagrammatic view of the trimmer mechanism showing it in its extreme upper and lower positions.

The sewing machine illustrated in the drawings comprises a substantially rectangular bed 1 having a standard 2 rising from the right rear corner thereof and carrying a bracket-arm 3 terminating in a head 4. As shown, the machine selected as a preferred embodiment of the invention is particularly adapted to do edge stitching and consequently the bracket-arm 3 has been made very short. It will also be noted that the standard 2 leans towards the front of the machine and that the head 4 is angularly related thereto, whereby the head will be substantially vertical and the needle-bar 5 and presser-bar 6 will reciprocate vertically. By means of the inclined

2

arm, there is provided a maximum of usable work-support area thus facilitating manipulation of the work while maintaining minimum dimensions of the bed 1.

Journalized in suitable bearings 7 and 8 located respectively in an end wall of the bracket-arm 2 and in a boss 9 integral with a side wall of the bracket-arm, is a rotary actuating shaft 10 having a combined belt-pulley and hand-wheel 11 secured to that end thereof that projects through the end wall of the bracket-arm. At its opposite end, the shaft 10 carries a counterbalanced crank 12 having a crank-pin 13 embraced by one end of a link 14 which, at its other end, has journalized therein a stud 15 secured to the needle-bar 5 for actuating the same. There is provided a single rotary take-up, generally indicated at 16, which is substantially the same as that disclosed and claimed in the co-pending application of Van Wagener et al., Serial No. 189,528, to which reference may be made for a more complete description thereof. A take-up guard 17 is secured to the end of the head 4 in the usual manner.

Depending from the under side of the bed 1 are walls 18 and 19 arranged longitudinally of the machine adjacent the front and back thereof, respectively. There are two legs 20 formed integral with the walls 18 and 19 at the one end thereof, and a single leg 21 formed integral with a boss 22 that depends from the bed 1. The boss 22 carries a rotary-hook assembly 23 and a bearing-sleeve 24. The hook-assembly as employed in this preferred embodiment of my invention is substantially the same as disclosed in the U. S. patent of Kessler, No. 2,441,937, May 18, 1948, to which reference may be had for a more complete description thereof. It is sufficient for the present disclosure to point out that the hook-assembly 23 includes an outer bearing-bushing 25 secured in a suitable aperture 26 drilled longitudinally in the boss 22 and having journalized therein a shaft 27 carrying a gear 28 at one end and a rotary-hook 29 at the other end, which hook is adapted to cooperate with a needle 30 carried by the needle-bar 5 in the formation of stitches in the usual manner. It will be noted that the outer diameter of the bearing-bushing 25 is larger than that of the gear 28, so that the hook-assembly 23 can be inserted in and withdrawn from the aperture 26 in the boss 22 as a unit.

The bearing sleeve 24 is secured in a suitable aperture 31 formed in the boss 22 and disposed parallel to the aperture 26. Journalized in the sleeve 24, by bearings 32, is a feed-lift shaft 33 that has its one end eccentrically reduced to form a crank-pin 34, and at its other carries a gear 35 having a hub portion 36 through which extends a set screw 37 that releasably secures the gear to the shaft 33. By removing the gear 35 from the shaft 33, it will be seen that the bearing sleeve and the enclosed shaft and bearing can be withdrawn from the aperture 31 as a unit, and conversely, these elements may be inserted into the aperture 31 after which the gear 35 may be secured to the shaft 33.

The gears 28 and 35 are enclosed by integral walls depending from the bed 1 which define a lubricant chamber 38 and which include an end wall 39 (see Fig. 2) formed as an integral downward extension of the wall 19 adjacent the leg 20, an end wall 40 opposed to the end wall 39, a side wall 41 that includes one face of the boss 22, and a side wall 42 opposed to the side wall 41. The bottom of the lubricant chamber 38 is closed by a cover-plate 43.

Formed in a boss 44, integral with the side wall 42 and depending from the bed 1, is an aperture 45 in which is removably secured a metallic bearing-bushing 46. To prevent oil within the lubricant chamber 38 from leaking out through the joint between the bushing 46 and the

aperture 45, there is provided a rubber ring gasket 47 seated in a peripheral groove in the bearing. This gasket effectively prevents any leakage of oil but readily permits withdrawal or insertion of the bushing 46 into the aperture 45. Anti-friction bearings 48 are seated in countersunk portions 49 at the end of a bore 50 through the bushing 46. Journaled in the bore 50 and bearings 48 is a shaft 51 that carries a gear 52, which is smaller in diameter than the bearing 46, upon that end located within the lubricant chamber 38 and a grooved pulley 53 upon the other end. A clip belt 54 is entrained about the pulley 53 and a similar pulley 55 secured to the shaft 10.

With reference to Figs. 3 and 4, it will be seen that the gears 28, 35 and 52 are arranged to rotate in a vertical plane and their axes of rotation lie substantially in a horizontal plane. The gears are thus in mesh in a series relationship, i. e., the gear 52, which is the driving gear and which receives power through the belt 54 from that supplied to the driven pulley 11, drives the gear 35 which in turn drives the gear 28. The pulleys 53 and 55 and the gears 52 and 35 each have a one-to-one ratio, while the gears 35 and 28 have a two-to-one ratio so that the hook will be operated at twice the speed of the other mechanisms in the usual manner.

The gears in the lubricant chamber 38 are automatically lubricated by the oil in the chamber which is supplied at least to the point where the gears 35 and 52 will be partly immersed, and which is churned by the action of the gears. The assembling of the mechanisms that project into the lubricant chamber 38 has been greatly simplified by the construction disclosed, since both the gears 28 and 52 are formed as parts of subassemblies that can be readily inserted into their proper positions in a preassembled condition which eliminates the time consuming task of assembling them in position. The gear 35 is secured to the shaft 33 in position which is done before either of the other two gears are inserted.

The feeding mechanism of the illustrated machine comprises a feed-dog 56 which, in the usual manner, coacts with a presser-foot 57 secured to the presser-bar 6. The feed-dog is carried at one end of a feed-bar 58 pivoted at the other end to a feed-advance rocker generally designated at 59 which is of conventional construction. Feed-lift movements are imparted to the feed-bar by a link 60 pivoted thereto as by a screw 61, which link embraces the eccentric reduced end 34 of the shaft 33. The rocker 59 is secured to a shaft 62 journaled in suitable bearing-bushings in two bosses 63 and 64 depending from the bed 1 adjacent the wall 19. Oscillation is imparted to the shaft 62 and consequently to the rocker 59, which effects the feed-advance and -return movements of the feed-bar, by a link 65 secured to the shaft at one end and pivotally connected at the other end to one end of another link 66. At its upper end, the link 66 embraces a wrist-pin 67 secured to one end of an anchor-link 68 which, at its other end, pivotally embraces a stud 69, one end 70 of which is embedded in a boss 71 integral with the head 4 of the machine. A collar 72 prevents the link 68 from coming off the stud 69. The forked lower end of a pitman 73 embraces the wrist-pin 67 on opposite sides of link 66. The pitman 73, at its upper end, terminates in a strap 74 that embraces an eccentric 75 formed as an element of an adjustable eccentric 76 such as disclosed in the U. S. patent of Myers, No. 2,128,031, to which patent reference may be had for a more complete understanding of the details thereof. It is sufficient for purposes of the present disclosure to point out that the eccentricity of the eccentric 75 relative to the shaft 10 can be varied by depressing the spring-biased detent 77 which releases the eccentric for rotation of the shaft 10 relative thereto and locks it in a stationary position, and then turning the shaft 10 by the hand-wheel 11.

The trimming mechanism is similar to that disclosed in the copending U. S. patent application of Breul, Serial

No. 140,481, filed January 25, 1950 and is mounted upon a guide pin 77 press-fitted into an aperture 78 in the head 4. Slidably mounted on the pin 77 is a sleeve 79 carrying a laterally projecting arm 80 terminating in a bifurcated end 81 that slidably embraces a secondary guide pin 82 press-fitted into an aperture 83 in the head 4. A slot 84 is cut into the arm 80 adjacent the bifurcated end 81 and a screw 85 is provided that projects through from one side of the slot and is threaded into the opposed side, whereby an adjustment of the opposed sides of the slot relative to each other may be obtained, which, of course, spaces the bifurcations at the end 81 so that they will closely but slidably embrace the sides of the guide pin 82.

Secured to the arm 80 by means of a screw 86 projecting through an elongated slot 87 formed in a horizontal leg 88 thereof, which screw holds said leg against a seat formed on said arm, is an angle-bracket 89 comprising, in addition to the leg 88, a vertical leg 90 depending from a horizontal leg 91 arranged at a right angle to the leg 88. A trimmer blade 92 is removably and adjustably secured to the lug 90 by screws 93, and is adapted to cooperate with a ledger blade 100 carried by the throat-plate 101 to sever the work adjacent the point of stitch formation. It will be seen (Fig. 3) that the cutting edge of the blade 92 is slanted with respect to the blade 100 so that there will be progressive contact between them.

Vertical reciprocation is imparted to the cutter blade by a toggle linkage similar to that disclosed and claimed in the U. S. patent of Pinkvoss, No. 2,202,599, and comprising a link 94 provided with a hub 95 which surrounds a pivot bolt 96 that also projects through an aperture in the arm 80. The link 94, at the end opposite from the hub 95, embraces a knuckle-pin 97 which is also engaged by the bifurcated end of a link 98 connected at its opposite end to the wrist-pin 67. The links 94 and 98 constitute a toggle which, when in the normal operative position as illustrated in the drawings, is beyond dead center position and locked by a releasable detent (not shown) to form a rigid connection between the wrist-pin 67 and pivot pin 96, whereby the oscillation of the wrist-pin 67 is transmitted to the pivot 96 and consequently to the blade 92. To break the toggle connection, there is provided a thumb-piece 99 integral with the hub 95, which can be depressed to release the detent and rotate the hub about its pivot 96 and thus move the link 94, knuckle-pin 97 and link 98 to the other side of its dead center position. With the toggle broken, the oscillation of the wrist-pin 67 is taken up in the knuckle-pin 97 and is no longer transmitted to the pivot 96, thus disabling the trimmer mechanism, which is held in a retracted position by a spring (not shown).

From the above, it will be evident that, when the toggle is locked, as the shaft 10 rotates, the adjustable eccentric 76 rotated therewith will impart substantially vertical reciprocation to the pitman 73 through the eccentric 75, which in turn, oscillates the wrist-pin 67 confined to motion in a single path by the anchor link 68. The oscillation of the wrist-pin 67 is transmitted to the feed-advance and -return mechanism by the link 66 and to the trimmer mechanism by the toggle links 94 and 98. Fig. 7 which is a schematic drawing of the elements, and in which the eccentric is set for maximum strokes of the feed mechanism and trimmer, the position of the elements when the trimmer is in its extreme upper position is illustrated in full lines while that position in which the trimmer is in its extreme lower position is illustrated in dotted lines. It will be understood that an adjustment of the eccentric 75 relative to the shaft 10 in such a manner as to reduce or increase the eccentricity will accordingly shorten or lengthen both the feeding stroke and the cutting stroke simultaneously and thus maintain corresponding motions between the two.

Numerous alterations of the structure herein disclosed will suggest themselves to those skilled in the art. How-

ever, it is to be understood that the present disclosure relates to a preferred embodiment of my invention which is for purposes of illustration only and not to be construed as a limitation thereof. All such modifications which do not depart from the spirit of my invention are intended to be included within the scope of the appended claims.

Having thus set forth the nature of the invention, what I claim herein is:

1. In a sewing machine having a bed, a standard, and an overhanging bracket-arm, stitch-forming mechanism, feeding mechanism comprising a feed-dog and feed-advance actuating mechanism for imparting a work-advance stroke to said feed-dog to advance the work past said stitch-forming mechanism, trimmer mechanism adapted to sever the work adjacent the point of stitch formation, including a stationary ledger blade and a movable trimming blade, a rotary shaft journaled in said bracket-arm, an adjustable eccentric secured to said shaft, a movable element, means for confining said element to motion in a predetermined path, a pitman operatively associated with said eccentric and said element whereby motion is transmitted to said element from said eccentric through said pitman, operative connections between said element and said feed-actuating mechanism to impart feed-advance movements to said feeding mechanism, and operative connections between said element and said trimmer mechanism including a manually breakable toggle linkage to impart work-severing movements to said trimming blade when said toggle is locked and to disable said trimming blade when said toggle is broken.

2. In a sewing machine having a frame including a bed, a standard, and an overhanging bracket-arm terminating in a head portion, a needle-bar slidably mounted in said head, and cooperating stitch-forming mechanism journaled in said bed, feeding mechanism comprising a feed-dog and feed-advance actuating mechanism for imparting a work-advance stroke to said feed-dog to advance the work past said stitch-forming mechanism, trimmer mechanism adapted to sever the work adjacent the point of stitch formation including a stationary ledger blade carried by said bed and a trimming blade slidably mounted in said head, an anchor link pivoted at one end on a horizontal axis to said frame, a wrist-pin secured to the opposite end of said link and thereby confined to motion in a predetermined path, selectively variable drive means for imparting motion to said wrist-pin, operative connections between said wrist-pin and said feed-actuating mechanism to impart feed-advance movements thereto, and operative connections between said wrist-pin and said movable trimming blade including a link extending through the bottom wall of said head to impart work-severing movements to said trimming blade.

3. In a sewing machine, stitch-forming mechanism, feeding mechanism comprising a feed-dog and feed-advance actuating mechanism for imparting a work-advance stroke to said feed-dog to advance the work past said stitch-forming mechanism, trimmer mechanism adapted to sever the work adjacent the point of stitch formation including a stationary ledger blade and a movable trimming blade, a wrist-pin, an anchor link confining said wrist-pin to motion in a predetermined path, selectively variable drive means for imparting motion to said wrist-pin, operative connections between said wrist-pin and said feed-actuating mechanism to impart feed-advance movements to said feeding mechanism, and operative connections between said wrist-pin and said trimming mechanism to impart work-severing movements to said trimming blade.

4. In a sewing machine having a bed, a standard, and an overhanging bracket-arm, feeding mechanism comprising a feed-dog and feed-advance actuating mechanism for imparting a work-advance stroke to said feed-dog to advance the work past a stitch-forming mechanism, trimmer mechanism adapted to sever the work adjacent the

point of stitch formation, including a stationary ledger blade and a movable trimming blade, a movable element, means for confining said element to motion in a predetermined path, a rotary shaft journaled in said bracket-arm, a rotary actuator secured to said shaft for imparting motion to said element, operative connections between said element and said feed-actuating mechanism to impart feed-advance movements to said feeding mechanism, and operative connections between said element and said trimmer mechanism to impart work-severing movements to said trimming blade, a bed-shaft journaled in said bed substantially parallel to said arm-shaft, drive connections between said bed-shaft and said arm-shaft, and operative connections between said bed-shaft and said feeding mechanism to impart feed-lift movements to said feeding mechanism.

5. In a sewing machine having a bed, a standard, and an overhanging bracket-arm, feeding mechanism comprising a feed-dog and feed-advance actuating mechanism for imparting a work-advance stroke to said feed-dog to advance the work past a stitch-forming mechanism, trimmer mechanism adapted to sever the work adjacent the point of stitch formation, including a stationary ledger blade and a movable trimming blade, a movable element, means for confining said element to motion in a predetermined path, a rotary shaft journaled in said bracket-arm, a rotary actuator secured to said shaft for imparting motion to said element, operative connections between said element and said feed-actuating mechanism to impart feed-advance movements to said feeding mechanism, and operative connections between said element and said trimmer mechanism to impart work-severing movements to said trimming blade, a lubricant chamber depending from said bed, a bed-shaft journaled in and extending through one wall of said lubricant chamber, drive connections between said arm-shaft and said bed-shaft, a feed-shaft journaled in and extending through one wall of said lubricant chamber, operative connections between said feed-shaft and said feeding mechanism to impart feed-lift movements to said feeding mechanism, and meshing gears secured to said feed-shaft and bed-shaft within said lubricant chamber.

6. In a sewing machine having a bed, a standard, and an overhanging bracket-arm, a stitch-forming mechanism, feeding mechanism comprising a feed-dog and feed-advance actuating mechanism for imparting a work-advance stroke to said feed-dog to advance the work past said stitch-forming mechanism, a movable element, means for confining said element to motion in a predetermined path, a rotary arm-shaft journaled in said bracket-arm, a rotary actuator secured to said arm-shaft, operative connections between said rotary actuator and said element to impart motion to said element, operative connections between said element and said feeding mechanism to impart feed-advance movements thereto, a lubricant chamber depending from said bed, a bed-shaft journaled in and extending through a first side wall of said lubricant chamber, drive connections between said arm-shaft and said bed-shaft, a feed-shaft journaled in and extending through a second side wall of the lubricant chamber, operative connections between said feed-shaft and said feeding mechanism to impart feed-lift movements to said feeding mechanism, and meshing gears secured to said feed-shaft and bed-shaft within said lubricant chamber.

7. A sewing machine having work feeding mechanism including a work advancing feed dog, feed lift mechanism for imparting rising and falling motions to said feed dog, feed advance mechanism for imparting advance and return motions to said feed dog, trimming mechanism including a stationary ledger blade and a complementary and relatively movable trimming blade, having progressively cooperating cutting edges whereby the work severing stroke of the trimming mechanism will be varied in accordance with the variations in the rela-

tive motion between said trimming blade and ledger blade; an actuating element, adjustable means for imparting variable actuation to said actuating element, and operative connections separately connecting said actuating element with said trimming mechanism and with said feed advance mechanism for imparting work advancing movement to said feed dog and reciprocatory movement to said movable trimming blade.

8. In a sewing machine having a bed, a standard, and an overhanging bracket arm, complementary stitch forming mechanism mounted in said bed and bracket arm, feeding mechanism mounting in said bed and comprising a feed dog, feed lift mechanism for imparting rising and falling motions to said feed dog, and feed advance mechanism for imparting advance and return motions to said feed dog, trimming mechanism adapted to sever the work adjacent to the point of stitch formation, and including a stationary ledger blade and a movable trimming blade having progressively cooperating cutting edges whereby the work severing stroke of the trimming mechanism will be varied in accordance with the variations in the relative motion between said trimming blade and ledger blade; a rotary shaft journaled in said bracket arm, a rotary actuator on said shaft, a movable element, means for confining said element to motion in a predetermined path, operative connections between said rotary actuator and said element for imparting motion to said element, operative connections between said element and said feed advance mechanism to impart actuation to said feed dog, and operative connections between said element and said trimming mechanism to impart actuation to said movable trimming blade.

9. In a sewing machine having a bed, a standard, and an overhanging bracket arm, complementary stitch forming mechanism mounted in said bed and bracket arm, feeding mechanism mounted in said bed and comprising a feed dog, feed lift mechanism for imparting rising and falling motions to said feed dog, and feed advance mechanism for imparting advance and return motions to said feed dog, trimming mechanism adapted to sever the work adjacent to the point of stitch formation and including a stationary ledger blade and a movable trimming blade having progressively cooperating cutting edges whereby the work severing stroke of the trimming mechanism will be varied in accordance with the variations in the

relative motion between said trimming blade and ledger blade; a rotary shaft journaled in said bracket arm, and adjustable eccentric on said shaft, a movable element, means for confining said element to motion in a predetermined path, a pitman operatively connecting said adjustable eccentric to said element for imparting motion to said element upon rotation of said eccentric, operative connections between said element and said feed advance mechanism to impart actuation to said feed dog, and operative connections between said element and said trimming mechanism to impart actuation to said movable trimming blade.

10. In a sewing machine, stitch forming mechanism, feeding mechanism comprising a feed dog, feed lift mechanism for imparting rising and falling motions to said feed dog and feed advance mechanism for imparting advance and return motions to said feed dog, trimming mechanism adapted to sever the work adjacent to the point of stitch formation and including a stationary ledger blade and a movable trimming blade having a cutting edge slanted with respect to the line of motion between said blades, a movable element, means for confining said element to motion in a predetermined path, selectively variable driven means for imparting motion to said element, operative connections between said element and said feed advance mechanism to impart feed advance movements to said feeding mechanism, and operative connections between said element and said movable trimming blade for imparting work severing movements thereto.
